UNITED STATES PATENT OFFICE

RAYMOND W. DULL, OF CHICAGO, ILLINOIS, ASSIGNOR TO LINK-BELT COMPANY, OF CHICAGO, ILLINOIS, A CORPORATION OF ILLINOIS

PROCESS OF CHAIN MANUFACTURE

Application filed May 7, 1924. Serial No. 711,533.

My invention relates to a process of making chain from a strip of sheet metal stock, and particularly to a process of continuously making the links and automatically assembling the links as they are made into the completed chain. The general object of my invention is to produce chain of the type herein described, in which hook and pintle tongues are stamped from the center 5 of the link blank and the hook and pintle end bars are bent to produce a chain, each link of which consists of flat side bars, a relatively cylindrical hook at one end and a pintle at the other end, shaped for rotation within the hook of the link next adjacent. One object is to provide a process for manufacturing chain of the type described, with maximum cheapness and simplicity. Another object is to provide a process for 10 the production of such chain in which the hook and pintle tongues are stamped from the center of the blank and curled into finished hooks and pintles with a minimum strain upon the metal of the blank and a minimum weakening and distortion of the 15 fibers of the metal. Another object is the provision of a process of scoring or indenting the individual blanks in order to reduce to a minimum the tendency of the end bar 20 to tear out. Other objects will appear from time to time in the course of the specification and claims.

I illustrate my invention more or less diagrammatically in the accompanying drawings, wherein—

Figure 1 is a plan view of the strip of material operated upon, illustrating the effect of the successive die impacts;

Figure 2 is a section along the line 2—2 of Figure 1;

Figure 3 is a plan view similar to Figure 1, but showing the under side of the stock;

Figure 4 is a skeleton side elevation of the punch and die, illustrating the passage 45 of the stock therethrough, and its formation into links;

Figure 5 is a view of a rounded punch which may be substituted for the pointed punches shown in Figure 4; and

Figure 6 is a longitudinal vertical sec-

tion through a slightly modified form of punch and die;

Figure 7 is a plan view of the die structure.

Like parts are illustrated by like characters throughout the specification and drawings.

A is any suitable base having mounted thereupon the die block A¹ which may be secured thereto in any suitable fashion.

B is any suitable strip of relatively resistant material upon which rests the individual die elements. These elements are gripped and aligned in any suitable manner and will later be discussed in detail.

The passage of the metal strip C over the die block is from right to left, as shown in Figure 4. This ribbon or strip of stock C may be initially straightened and fed by any suitable means not herein shown, being guided into the machine for example by the yieldingly mounted supporting block C¹, which is mounted to reciprocate vertically in the die block A¹, being supported, for example by the spiral spring C², its vertical movement being limited in any suitable fashion. C⁵ is a centrally disposed flat bearing surface thereon, adapted to receive the bottom of the strip C and upon which the strip may be centered, for example by a pair of opposed set screws C⁶, which may be adjusted to adjust the strip C laterally.

D is a second strip or stock supporting yoke or block slidable along vertical pins D² and upwardly pressed by the spiral springs D³ against the heads D⁴ of the pins.

P, P are conical prick punch elements mounted in the yoke D, the purpose of which will be later described.

Positioned to the left of the support D, as shown in Figure 4, are a pair of opposed strip or stock guiding elements E adapted to reciprocate in the apertures E¹ in the block A¹, the lower portion of each serving as a plunger to guide this reciprocation. They are normally maintained in a position of maximum elevation by the coiled springs E⁵ which penetrate the cylindrical apertures E⁶ in the guide elements. The upper portion of the guide elements are laterally in-

wardly slotted to engage the edge of the stock or strip which may be centered between the opposed guides, for example by the set screws E⁹.

5 G is a stock engaging element having a pair of upwardly projecting, longitudinally extending lugs G¹, G¹ adapted to engage the side bars of the link blank. It rests upon the tops of a pair of plungers G², the lower extremities of which are fixed in a yoke G³ slidable along the pin G⁴. G⁵ is a spiral spring compressed between the yoke G³ and the stock G⁶ adjacent the lower extremity of the pin. G⁷, G⁷ are adjusting nuts screw 10 threaded upon the lower portion G⁸ of the pin.

15 Mounted still farther to the left, as shown in Figure 4, are a pair of opposed channel iron guides H, H, adapted to engage the opposite sides of the chain links. Any suitable means may be provided for drawing them forwardly therealong, said means being not shown herein, and forming no part of the invention claimed in the present application. The channels H are connected, for example, by cross pieces H¹, the ends of which are perforated to slide upon the pairs of vertical guides H², and are kept normally in raised position, as shown in 20 Figure 4 by the spiral springs H³. The heads H⁴ of the pins serve as stops to limit the upward movement of the cross piece H¹.

25 The chain is formed by the passage between the opposed die and punch elements of a strip of stock which is moved forwardly therebetween by a step by step movement, by any suitable feeding means, the details of which need not be shown herein. At each successive forward movement the punch element is moved downwardly against the die element by any suitable press mechanism. The punch block K is clamped into any suitable working backing K¹, for example by the set screws K². K³ is a backing or base element similar to the backing or base B of the die block, and adapted to engage the inner ends of the individual punch elements. 30

35 The punch and die elements are for purposes of description arbitrarily grouped into the members or areas operating simultaneously upon the link blank as it passes step by step therebetween, and will be described in relation to the impression they successively make upon the blank. As the stock C is passed forwardly through the guide C¹ it is first engaged by opposed indented or striated gripping pads L, L¹, L being fixed in relation to the die block A¹, L¹ being yieldingly mounted in the punch block K, and 40 being held in normally downwardly extended position, for example, by the spiral spring L². The function of the opposed pads is to grip the stock and prevent lateral movement thereof during and in response to the 45 successive forming impacts, their action be-

ing particularly important when the strip is first fed through between the punch and die and before its end has reached the opposite end of the die. The pads may be of metal, or of any suitable fibrous or frictional material. At each forward step or movement, that part of the stock which has just been gripped by the pads L, L¹ is moved forwardly a predetermined length, the length of one chain link blank, and is then subjected to the action of a pair of prick punches L², L² on the die, and a transverse scoring knife L³ on the punch. The prick punch elements are so positioned as to indent the inner corners of the junctions between the side bars and the pintel end bar, on the lower side of the stock along the line of future division between the tongues which will ultimately be separated from the side bars to form the hook and pintle of the completed link.

50 Whereas I prefer to use sharp pointed prick punches, it will be understood that under some circumstances a rounded or ball tipped punch or indenting instrument can be substituted which will have the same function and perform the same service. The alternative type of prick punch is illustrated as P in Figure 5.

55 At the next forward movement of the stock the blank or future link is so positioned that the transverse severing knife L⁵ overlies the score l³ and severs the metal therealong, cutting apart the edges of the opposed hook and pintle tongues, bending the pintle tongue downwardly about the bead L⁴ and slightly bending the end of the hook tongue and beginning its separation from the side bars, as shown in Figure 2.

Meanwhile, the opposed pairs of longitudinal scoring knives L⁶, L⁷ score or outline the unsevered or uncut edge of the hook tongue on the top and bottom of the stock respectively, as shown at l⁷ in Figure 1 and l⁶ in Figure 3.

105 At the next forward movement of the stock it passes above the yielding block D, above described, and the bottom of the stock is pinched by the prick punch elements D¹⁰ thereupon, the prick punch marks coming at the ends of the bottom longitudinal scores l⁶ and indicating the inner corners of the junction between the side bars and the hook end bar of the link. The punch marks serve to prevent tearing out of the stock when the hook tongue is severed from the side bars along the longitudinal scores l⁶, l⁷.

110 The knife L¹¹ further bends the ends of the pintle and hook tongues, the end of the pintle tongue being bent about the beading L¹² and the end of the hook tongue being rolled about the rounded corner L¹⁴ of the yieldingly mounted block D. The hook tongue is thereby separated from the side 115 bars.

bars along part of the length of the longitudinal scores l^1 , l^2 .

At the next forward movement of the stock the punch element L^{16} completes the separation of the hook tongue from the side bars, moving it to the position shown at l^{16} in Figure 2, the punch marks l^{16} preventing tearing away of the hook tongue at the corners. Meanwhile the transverse scoring knife L^{20} deeply scores the top of the stock, outlining the separation between adjacent links, and the end of the punch element L^{16} further slightly bends the pintle tongue about the transverse bead L^{18} , along the left edge of the block D, as shown in Figure 4.

At the next forward movement of the stock the punch element M which has substantially the cross section of the central aperture of the link, punches out or moves the hook tongue to the position shown at m^1 in Figure 2. Along the base of the punch M are the inclined punch ledges M^2 adapted to engage the side bars of the link and bend them into the position shown at m^3 in Figure 2. The rounded ends M^4 , M^5 of the base of the punch block M, operating against corresponding die elements, bend the hook and pintle end bars respectively of the link to the form shown at m^6 , m^7 in Figure 2.

The punch M near the pintle end is slightly wider, as at M^9 than the central aperture of the link, and chisels out a part of the aperture to allow freedom for the hook in the finished chain.

Finally at the next movement of the stock the cutting edge N, formed by a downward off-setting of the punch, shears along the score l^{20} and against the opposed cutting edge N^1 of the die, and severs the partly completed link from the stock. As the stock is forced down by the punch, prior to the severing, the side bars of the link are engaged by the longitudinal lugs G^1 of the yieldingly mounted block G, and are locked thereby against the punch element N^2 , which is provided with a central portion N^3 penetrating within the central aperture of the link, and side bearing surfaces N^4 in opposition to the tops of the lugs G^1 . The severed link is thus firmly gripped, the spring G^5 serving to compress the block G and the lugs G^1 against the link, and to lock the link against the punch N^2 .

The curved portions N^5 , N^6 of the punch N^2 engage respectively the bent hook and pintle end bars. As the link is carried downwardly by the punch, the end of the hook tongue engages the rolling die surface N^6 and is curved thereby into the position N^7 , as shown in Figure 4. Prior to the completion of this rolling movement the pintle tongue contacts the die surface N^8 and is bent into the position shown in Figure 4. The rolling movement of the hook tongue is

limited by the stop N^{10} adjacent the surface N^5 of the punch element N^2 .

Meanwhile the previously completed links of the chain are passing forwardly between the guides H, the forward feed of the chain being so adjusted that as each hook tongue is rolled into the position shown at N^7 , the pintle tongue and pintle bar of the precedingly formed link is held in the position shown at O in Figure 4. The hook tongue curls around and incloses it, thus fastening the newly formed link to the end of the completed chain, as shown in dotted lines at O^1 in Figure 4.

The guides H and the completed chain travelling therethrough are normally maintained in general alignment, as in Figure 4, with the stock as it passes through the yieldingly supported guide elements C¹ and E. As the stock is depressed by the action of the punch elements thereupon, the punch also contacts the cross elements H¹, and depresses the finished chain, maintaining it in alignment with the stock as it descends and with the descending severed link as it continues its descent following severance from the stock. As the hook tongue of the link begins to curl, as at N^7 , the pintle bar of the finished link is dropped into position in the bend of the hook tongue and is thus surrounded by it as the hook tongue is rolled into final position. At the next forward movement of the stock and the completed chain, the completed link is drawn forward with the completed pintle bar ready for the attachment of the next succeeding link thereto.

In the modification shown in Figure 6, the initial scoring knife L^3 is shown as in Figure 4. It has opposed to it a smaller scoring knife T which is just sufficient to cut the skin or surface of the metal of the underside of the strip C. In order to prevent compression of the metal and consequent breaking down and weakening of its structure, I provide at each side of the scoring knife T the depressions T¹, T². The scoring or creasing knife T² serves to crease the bottom of the stock along the inside of the bend of the future pintle tongue. The prick punch elements L² are shown as moved forward one step to occupy the position of the pad L in Figure 4, and the pad L may be moved forward, or may, if desired, be dispensed with.

The use and operation of my invention are as follows:

I manufacture chain from a ribbon or strip of sheet metal stock which is fed forwardly step by step between opposed punches and dies. The interval between the forward feeding movement need be only sufficient to permit the strip to move forwardly through the press the length of one link.

In order to prevent interference between the stock and the punch or die, at the time of stock forward movement, I provide means for lifting the entire strip of stock from the die between the forming impacts of punch upon die. In the form herein shown, I move the strip upwardly, after each impact, to a position substantially midway between punch and die when the punch is withdrawn to its maximum height. In the illustrated mechanism, I accomplish this result by feeding the strip forwardly through yieldingly mounted guides which are adapted normally to support the stock a predetermined distance above the dies, but which permit it to descend, and descend with it, in response to the action of the punch. As the punch descends, it forces the strip and with it the strip guides downwardly toward the die block, and as soon as the punch withdraws, the guides rise and carry the strip with them. I center the strip in relation to die and punch by means of set screws or other adjusting mechanisms on the yieldingly mounted guides or supports.

In the form of punch and die herein shown, the portions which are forced out of the normal plane of the strip are all bent downwardly toward the die. It is therefore necessary to lift the strip above the die a distance greater than the length of the largest downward projection, namely the hook tongue.

In the method of forming chain herein described, the side bars of the chain are not deformed or bent until shortly before the link is severed from the chain stock. Therefore the stock throughout most of its excursion between the punch and die has straight edges, and can easily and efficiently be fed forwardly through the guides.

The strip metal stock, of which the links are formed, is a fibrous material, and of course tough and hard. In making links from it it is necessary not only to render easy the severing of the parts which have to be severed, and to make this severing possible without distortion of the stock, but also to limit the severing and to counteract the tendency for further and unintended tearing or severing, either during manufacture or during later use of the chain. To make the severing easy, the parts to be severed are initially scored. To prevent further unintended tearing the lines of score are terminated by indentations which break up the normal fibrous structure of the material. The major severing operations are performed, not by one impact, but by a succession of impacts. The distortion of the metal at any one point is reduced to a minimum, and sharp bends, or corners, where the material of the stock is compressed by bending, are provided with creases or indentations which serve to give space for

the material compressed, for example along the pintle tongue and at the corners of pintle and hook tongues, where they are bent from the stock.

The successive steps of the operation are 70 as follows:

1. The gripping step, the action of the opposed gripping pads, one fixed and one yielding, one on the punch and one on the die. These opposed pads grip the metal stock and prevent its longitudinal movement. Their action is important primarily during the initial feed of the stock through the press, and the chain forming process may be carried on without them, although under many conditions they are valuable.

2. The center of the link is next transversely scored as at l^3 to outline the separation between the opposed edges of hook and pintle tongues. In the mechanism herein shown this score is across the top of the stock, but of course the location of this and of the other score and punch marks herein described could be inverted. The opposite side of the stock is indented as at l^2 , l^2 , the punch marks indicating the corners of the future central aperture of the link, and breaking up the regular fibrous structure of the metal at those points.

3. As the strip moves forwardly one step, the same area is next operated upon by the opposed scoring knives l^6 , l^7 which outline, upon the top and bottom of the link, the separation between hook tongue and the side bars. These scores do not extend as far as the transverse score l^3 , but this is not necessary, since the transverse severing knife l^5 at the same time severs the stock along the score l^3 and bends back the pintle tongue and the end of the hook tongue, the scores l^6 , l^7 reaching substantially to the point at which the hook tongue is separated from the side bars. The pintle tongue is bent about the bead L^4 , which makes a transverse crease along the inside of the bend, and connects the already formed indentations l^2 , l^2 . Space inside the bend is thus provided to take up the compression of the metal when the pintle tongue is further bent, and any tendency of the pintle tongue to tear out at the corners is obviated by the indentations l^2 , l^2 .

4. At the next forward movement of the stock the top of the stock receives the impact of a transverse punch element aligned with the original separation between hook and pintle tongues. One side of this element further bends the pintle tongue, and bends it about a bead L^8 , which further enlarges the groove or crease along the inside of its bend. The other side further bends the end of the hook tongue continuing its separation from the side bars, and gives to its end a curve, substantially concentric with the future arc of the finished hook. Meanwhile the bottom of the stock is punched as at l^{10} , l^{10} , the

punch marks closing the ends of the scores l^e , and serving to prevent the tendency of the link to tear out when the hook tongue is finally bent away from the stock.

5. At the next forward movement of the stock the hook tongue is operated upon by a punch element which completes its severance from the link side bars and bends it to the position l^{16} in Figure 2. The previously made indentations l^{10} , which have broken up the fibrous structure of the corners of the link, prevent weakness and tearing at the base of the hook tongue.

6. At the next forward movement of the stock the downwardly depending pintle tongue drops over the corners of the die element m^{20} , and prevents longitudinal distortion of the entire strip to the rear of the point, or shortening of the strip or of the individual links by the impact and distortion action of the forming punches.

Up to this point the sides of the stock have been straight, since there has been no distortion of the side bars. Now, however, the line of separation of the two adjacent links is made along the score l^{20} and the link thus separated, is bent to the position shown at the left end of the Figure 2. Meanwhile the hook and pintle bars are bent into the position shown at m^5 , m^7 and the central aperture of the link adjacent the pintle bar is slightly widened as at m^9 .

7. The link is now ready to be severed from the stock and at its next forward movement it is sheared along the score l^{20} and is carried downwardly by the punch element n^2 toward the lower forming die. The hook tongue m^1 , since it depends farther from the link than the pintle tongue, is the first to contact the die and is rolled around by the semi-cylindrical die surface n^6 into the form shown at n^7 in Figure 4. When the link has been carried so far down that the pintle tongue also contacts the die, it is bent into finished form. Since it is bent or compressed far more highly than the longer hook tongue, the creases or grooves along the inside of the bend of the pintle tongue are extremely important in preventing weakening of the pintle tongue, and the punch marks at the corners are vital in preventing strain upon and distortion of the metal at those points.

The pintle of the precedingly completed link is positioned within the arc of the hook tongue as it is being curled into final form, and it therefore curls about the pintle and passes through the central aperture of the preceding link. The pintle end of the link being somewhat widened, as at m^9 , there is ample room for the hook tongue to pass therethrough. The link thus completed is drawn forwardly away from the end of the stock and at the next movement of the stock

the succeeding link is fed forward ready for separation and final formation.

In the form shown in Figure 6 I have illustrated a means for minimizing the effect of the transverse scoring knife in breaking up and weakening the structure of the metal. I provide an opposed scoring knife just sufficient to break the surface of the lower side of the stock, and I position it between transverse indentations T^1 which give space for the metal displaced by the scoring knife L^3 . Strain upon the metal is so far eliminated as to prevent any appreciable weakening of the fibrous structure of the future link. I also indicate in Figure 6 the creasing element T^2 which scores or creases the inside of the bend of the future pintle tongue, making easier its bending and enabling it to be bent with a substantially reduced strain upon and weakening of the fibrous structure of the metal. I may dispense with the prick punches, or I may move them a step forward on the die, as shown in Figure 6.

While I have illustrated an adequate and operative device, and a practical and efficient process, it will be realized that I do not wish to be limited to the specific details and steps shown, or to the specific order of steps. I wish my description to be taken rather as in a broad sense diagrammatic, and illustrative, since many changes in form and arrangement of steps and the parts used to accomplish the steps may be made without departing from the spirit of my invention.

I claim:

1. The process of making chain from a continuous strip of sheet metal stock, which consists in scoring said stock to outline the inner edges of the side bars of the links, severing the metal between said scores and progressively separating a tongue of metal within said scores from the side bars, along the lines of score, by successive impacts upon the tongue, and maintaining the end bars undeformed and in the plane of the stock during such impacts until after the separation of the tongue from the side bars is completed.

2. The process of making, from a continuous strip of sheet metal stock, chain comprising links having pintles and hooks struck from the center of the link blank, which consists in first transversely scoring the central portion of the stock prior to the operation thereon of any forming or severing members; then longitudinally scoring the stock to outline the inner edges of the side bars and separating the opposed ends of hook and pintle tongue along the transverse score, and rolling them apart in like direction away from the plane of the stock; then separating the hook tongue from the side bars along the line of score; and finally severing the blank from the stock and rolling the hook tongue about the pintle of the next

preceding link; and maintaining the side and end bars of the link blanks flat and unextended until the separation of the hook and pintle forming tongues from the side bars is completed.

3. The process of making, from a continuous strip of sheet metal stock, chain comprising links having pintles and hooks struck from the center of the link blank, which consists in first transversely scoring the central portion of said stock; then longitudinally scoring the stock to outline the inner edges of the side bars of the links and tearing apart the opposed ends of hook and pintle tongues, and rolling them apart along said transverse score in like direction from the plane of the stock; then bending the outer end of the hook tongue into substantially arcuate cross section; then downwardly bending the hook tongue and completing its separation from the side bars; then further bending the hook tongue from the side bars, and bending the entire blank downwardly from the hitherto unbent stock.

4. The process of making, from a continuous strip of sheet metal stock, chain comprising links having pintles and hooks struck from the center of the link blank, which consists in longitudinally scoring the stock to outline the inner edges of the side bars, and severing the metal between said longitudinal scores; then indenting said stock adjacent the junction of the side bars and the hook end bar toward which the tongues are to be bent, and separating the hook and pintle tongues from the side bars, by bending them in the direction of the indented side of the stock.

5. The process of making, from a continuous strip of sheet metal stock, chain comprising links having pintles and hooks struck from the center of the link blank, which consists in indenting the blank adjacent the junction of the side bars and the pintle end bar, longitudinally scoring the stock to outline the inner edges of the side bars, severing the metal between said longitudinal scores, indenting the stock adjacent the junction of the side bars and the hook end bar, and separating the hook and pintle tongues from the side bars by bending them in the direction of the indented side of the stock.

6. The process of making, from a continuous strip of sheet metal stock, chain comprising links having pintles and hooks struck from the center of the link blank, which consists in indenting the blank adjacent the inside corners of the junctions of the side bars and the end bars, longitudinally scoring the stock to outline the inner edges of the side bars, severing the metal between said longitudinal scores, and separating the hook and pintle tongues from the side bars by bending them in the direction of the indented side of the stock.

7. The process of making, from a continuous strip of sheet metal stock, chain comprising links having pintles and hooks struck from the center of the link blank, which consists in indenting the stock at the junction of the side bars and the pintle end bar and transversely scoring the central portion of the stock to outline the abutting edges of the hook and pintle forming tongues; then longitudinally scoring the stock to outline the inner edges of the link side bars; then separating the hook and pintle tongues from each other; then indenting the stock at the junction of the side bars and the hook end bar on the same side of the blank as the previous indentation, and bending the hook and pintle tongues in the direction of the indented side of the stock.

8. The process of making, from a continuous strip of sheet metal stock, chain comprising links having hooks and pintles struck from the center of the link blank, which consists in first indenting the blank adjacent the intersection of the side bars and the pintle bar, and transversely scoring the blank; then longitudinally scoring the stock to define the inner edges of the side bars, and transversely severing the stock between such scores, and creasing and bending the pintle tongue and bending the outer end of the hook tongue; then further bending the pintle tongue and bending and forming the outer end of the hook tongue to conform substantially to the arc of the latter formed hook, indenting the blank adjacent the intersection of the side bars and the hook end bar, and beginning the separation of the hook tongue from the side link bars along the lines of score; then further creasing the pintle end bar and bending the pintle tongue substantially at right angles to the stock and at the same time shearing the hook tongue from the side bars along the lines of longitudinal score, and bending it at a substantial angle to the stock; then transversely scoring the stock along the line of separation of the adjacent blanks and at the same time crimping the hook end bar, the ends of the side bars and the pintle bar, and bending the entire blank to a slight angle in relation to the hitherto flat stock; then shearing off the blank and bending the pintle tongue into final position and rolling the hook tongue substantially cylindrically about the pintle of the link previously formed.

9. The process of making from a continuous strip of sheet metal stock, chain comprising links having pintles and hooks struck from the center of the link, which consists in moving said strip forwardly between opposed punch and die elements, striking out the center of each link to form a tongue projecting at a substantial angle

from the stock, and opposing said tongue to one of the die elements to prevent longitudinal slipping of the stock at the moment of impact of opposed punch and die.

10. The process of making, from a continuous strip of sheet metal stock, chain comprising links having pintles and hooks struck from the center of the link blank, which consists in outlining opposed hook and pindle forming tongues, separating them from each other, and completing their separation from the side bars, unextended, and crimping the hook and pindle end bars out of the plane of the side bars, and bending the link blank at an angle to the stock, in the direction in which the tongues had previously been bent.

11. The process of making, from a continuous strip of sheet metal stock, chain comprising links having pintles and hooks struck from the center of the link blank, which consists in outlining opposed hook and pindle forming tongues, separating them from each other, and completing their separation from the side bars while maintaining the side and end bars of the link blanks flat and unextended; bending the hook and pindle end bars out of the plane of the side bars after the separation of said tongues from the side bars, and bending the link blank at an angle to the stock, in the direction in which the tongues had previously been bent; and then severing the blank, bending the pindle tongue into final shape, and rolling the hook tongue about the pindle of the previously completed link.

12. The process of making, from a continuous strip of sheet metal stock, chain comprising links having pintles and hooks struck from the center of the link blank, which consists in transversely scoring the center of the link blank; then severing the metal along such score, bending the pindle tongue, while creasing the inside of its bend, and bending the end of the hook tongue; then further bending the pindle tongue, further bending the end of the hook tongue; and beginning its separation from the side bars; then further bending the pindle tongue and completing the separation of the hook tongue from the side bars.

13. The process of making, from a continuous strip of sheet metal stock, chain comprising links having pintles and hooks struck from the center of the link blank, which consists in indenting the inner corners of the intersections of the side bars and the end bars of the blank, severing the hook and pindle tongues from each other and from the side bars, and bending them away from the side bars in the direction of the indented side of the blank, and bending the hook tongue about the pindle of the precedingly completed link.

14. The process of making, from a con-

tinuous strip of sheet metal stock, chain comprising links having pintles and hooks struck from the center of the link blank, which consists in passing said stock forwardly between opposed punch and die elements, lifting said stock from said guide after each forming impact and supporting said stock between and out of contact with said punch and die elements between the forming impacts at a plurality of points longitudinally opposed along said stock, and feeding said stock forward while so supported.

15. The process of making, from a continuous strip of sheet metal stock, chain comprising links having pintles and hooks struck from the center of the link blank, which consists in passing said stock forwardly between opposed punch and die elements, and subjecting each link successively to their forming action, severing the link from the stock prior to completing the rolling up of the hook tongue, carrying said link downwardly below the plane of the die, positioning the chain with the pindle of the link last completed within the periphery of the arc to be described by the hook tongue in course of its formation, carrying said completed link downwardly in unison with the descent of said link, and curling said hook tongue about the pindle of said link in response to the downward movement of said hook tongue against a forming die.

16. The process of making, from a continuous strip of sheet metal stock, chain comprising links having pintles and hooks struck from the center of the link blank, which consists in transversely scoring the central portion of said stock to outline the separation between the hook and pindle tongues and at the same time transversely scoring the inside of the bend of the future pindle tongue; then longitudinally scoring the stock to outline the inner edges of the side bars, and severing the metal between said longitudinal scores along said transverse score; then separating the hook tongue from the side bars along the lines of score.

17. The process of making, from a continuous strip of sheet metal stock, chain comprising links having pintles and hooks struck from the center of the link blank, which consists in passing said stock forwardly between opposed punch and die elements in a step by step movement, engaging the edges of the stock and lifting said stock to a position between and out of contact with said punch and die elements, between the forming impacts, and in feeding said stock forward one step, between each forming impact, while so supported, and holding it against lateral movement.

18. The process of making, from a continuous strip of sheet metal stock, chain comprising links having pintles and hooks

struck from the center of the link blank, which consists in passing said stock forwardly between opposed punch and die elements in a step by step movement, engaging the edges of the stock at a plurality of points longitudinally spaced there along, and lifting said stock to a position between and out of contact with said punch and die elements, between the forming impacts, feeding said stock forward one step, between each forming impact, while so supported and holding it against lateral movement and maintaining the edges of the stock substantially unbent and in substantially the same plane until after the hook and pintle tongues have been completely separated from the side bars of the link.

Signed at Chicago, county of Cook and State of Illinois, this 29th day of April, 1924.

RAYMOND W. DULL.
